United States Patent

Des. 240,158
Patented June 1, 1976

240,158

FOAM INSULATION APPLICATION UNIT

Henry Sperber, assignor to Ark-Seal Corporation,
Denver, Colo.

Filed Mar. 29, 1974, Ser. No. 455,983

Term of patent 14 years

Int. Cl. D15—99

U.S. Cl. D55—1 R

FIG. 1

FIG. 2

FIG. 1

FIG. 2

FIG. 3

FIG. 4

FIG. 5

FIG. 6

FIG. 1 is a front view of a foam insulation application unit of the invention;

FIG. 2 is a rear view thereof;

FIG. 3 is a top view thereof;

FIG. 4 is a bottom view thereof;

FIG. 5 is a side view thereof; and

FIG. 6 is a perspective view thereof.

The hoses are shown broken to indicate indeterminate length.

I claim:

The ornamental design for a foam insulation application unit, as shown and described.
